United States Patent Office

Des. 220,614
Patented May 4, 1971

220,614

CUTTING BLOCK

Leonard K. Reichert, 16 Euston St.,
Brookline, Mass. 02146

Filed Dec. 12, 1969, Ser. No. 20,476

Term of patent 14 years

Int. Cl. D15—12

U.S. Cl. D11—1

FIG. 1

FIG. 3

FIG. 4

FIG. 1 is a perspective view of a cutting block showing my new design;

FIG. 2 is a bottom perspective view thereof;

FIG. 3 is an elevational view of the end of the block opposite that shown in FIG. 1;

FIG. 4 is a perspective view of a second embodiment of my new design.

I claim:

The ornamental design for a cutting block, substantially as shown and described.
